UNITED STATES PATENT OFFICE.

JEAN PIERRE SERVE, OF GIVORS, FRANCE.

APPARATUS FOR PICKLING TUBES.

SPECIFICATION forming part of Letters Patent No. 440,511, dated November 11, 1890.

Application filed August 7, 1889. Serial No. 320,043. (No model.) Patented in France February 15, 1889, No. 196,106, and in Italy July 1, 1889, No. 25,745.

To all whom it may concern:

Be it known that I, JEAN PIERRE SERVE, manufacturer, a citizen of the Republic of France, and a resident of Rue des Servettes, 5 Givors, (Rhône), France, have invented certain new and useful Improvements in Apparatus for Pickling Tubes, (for which I have obtained patents in France, No. 196,106, dated February 15, 1889, and in Italy, No. 25,745, 10 dated July 1, 1889), of which the following is a specification.

The improved apparatus for pickling metal tubes of any kind, which forms the subject of this invention, is designed to enable the 15 realization of certain important advantages, which I will state summarily.

The present invention is economical, because it permits the pickling to be restricted to the interior of the tubes, while the means 20 heretofore employed have necessitated the pickling of their exterior surface as well as their interior surface and a corresponding expenditure of acid. Moreover, the said invention permits the preservation of the thin 25 layer of metallic oxide which covers the exterior surface of the tubes, and which, under the special conditions in which it is generally produced, has the effect of insuring to a remarkable extent the ulterior preservation of 30 these tubes.

The invention consists in the features of construction, the combination or arrangement of parts, and the principles of operation hereinafter described and claimed, reference being made to the accompanying drawings, in 35 which—

Figure 1 is a longitudinal vertical sectional view of an apparatus embodying my invention. Fig. 2 is a transverse sectional view of 40 a modified construction.

To perform the pickling operation I arrange at a sufficient depth below the surface of the ground or floor P P of the place where the operation shall take place a trough A, 45 lined with lead, as at a, Fig. 1, and provided in proximity to its upper part with a cross-bar T, covered with a thick pad C, of india-rubber or other material suitable for the purpose, as hereinafter set forth. The distance at which 50 this cross-bar is placed below the aforesaid floor must be adapted to the length of the

tubes in order that their upper part shall be within reach of the workman standing on the said floor.

Upon the above-mentioned pad of india-rubber or other material is supported one of the extremities of the tube, which has been carefully cut square in such a manner that the weight of the tube will be sufficient to make a tight joint between its lower extremity 60 and the said pad.

At a suitable height above the tube D is arranged a second trough A', similar to the first and having a series of cocks R R or india-rubber pipes provided with clamps or the like corresponding to the series of tubes placed vertically or otherwise below them. In case the tubes are inclined the aforesaid pad must be arranged at such an inclination that a tight joint will invariably be formed. 70 Under these conditions it is easy to completely fill the tubes with acidulated water and then allow them to remain in this state for the time deemed sufficient for the pickling. When this operation has been terminated, it is sufficient to slightly displace or incline the tubes in order to allow the liquid which they contain to run out directly into the lower trough. The tubes are then transported to the desired spot to be washed, dried, 75 and finally subjected to the polishing operation. In this manner the acid liquid contained in the upper trough A' will gradually descend into the lower trough A, whence it is subsequently raised again into the upper 80 reservoir through the medium of pumps or any other device suitable for this purpose.

In the modification, Fig. 2, I employ two lower troughs A, lined with lead, as at a, and connected by a tube B for keeping the level 90 of the acidulated water in the two tanks at the same height. A single upper trough A', with cocks R at opposite sides, is employed, and each lower trough A contains a cross-bar T and an india-rubber pad C, as explained 95 with reference to Fig. 1. The arrangement in Fig. 2 is desirable in that it permits a greater number of tubes to be pickled at the same time.

What I claim is—

1. A tube-pickling apparatus consisting of a trough for receiving the acid from the tubes,

- an elevated yielding and impermeable pad for supporting and making a tight joint with the lower extremities of the tubes being pickled, and means for introducing the acid 5 into the tubes, substantially as described.
2. A tube-pickling apparatus consisting of a trough for receiving the acid from the tubes, a cross-bar supported in the trough and provided on its upper side with a yielding and 10 impermeable pad for supporting and making a tight joint with the lower extremities of the tubes being pickled, and means for introducing the acid into the tubes, substantially as described.
- 15 3. A tube-pickling apparatus consisting of a lower trough for receiving the acid from the tubes, a pad of india-rubber, or other yielding or impermeable material for making and supporting a tight joint with the lower extremities of the tubes to be pickled, and an 20 upper trough having pipes or cocks for introducing the acid into the tubes, substantially as described.

In testimony whereof I have hereunto signed my name in the presence of two sub- 25 scribing witnesses.

JEAN PIERRE SERVE.
